UNITED STATES PATENT OFFICE.

OLIVER C. MADISON, OF OMAHA, NEBRASKA.

TOY GUN.

1,168,815.

Specification of Letters Patent. Patented Jan. 18, 1916.

Application filed March 31, 1913. Serial No. 758,012.

To all whom it may concern:

Be it known that I, OLIVER C. MADISON, a citizen of the United States, and a resident of Omaha, in the county of Douglas and 5 State of Nebraska, have invented certain new and useful Improvements in Toy Guns, of which the following is a specification.

My invention relates to toy guns or pistols wherein a suitable projectile is thrown by 10 means of a spring.

It is the object of my invention to provide a simple and inexpensive device of this kind, wherein the barrel, handle, trigger and projectile detent are formed from a single piece 15 of wire, and of which the general outline is a close simulation of a pistol or revolver.

A structure embodying my invention is illustrated in the accompanying drawings, in which—

20 Figure 1 is a side view of the toy, Fig. 2 is a plan view thereof, and Fig. 3 is a detail transverse section on the line $x-x$ of Fig. 1.

In carrying out my invention the main body or frame of the toy is made from a 25 single piece of wire of suitable size and preferably of such temper as to permit it being bent without annealing or subsequent retempering, and sufficiently resilient to permit a slight distortion from the normal 30 form without causing a permanent change or "set" of the parts to the distorted form. The said main body or frame comprises the rectilinear barrel-portion 1, the double-bend or looped breech-body 2, the rearward part 35 3, butt 4 and front part 5 of the handle or grip, the loop or trigger-portion 6, the return-bend 7, the arch-portion 8, the stem 9 and the hook or catch 10. A strip 11 of sheet-metal is placed around the rearward 40 part of the barrel 1 and breech-body 2, and around the upper part of the return-bend 7. The ends of the strip are curled in between the upper and lower parts of the breech-body 2, as shown in Fig. 3, and the embraced portion of the return-bend 7 passes 45 slidably through the lower loop of the strip. The strip serves to hold the engaged parts together and thus imparts a considerable lateral stability to the frame. A helical coil 50 spring 12 is disposed around the barrel at the rearward end thereof, the rear end of the spring being looped into the forward part of the breech-body 2 so that said end of the spring is held in fixed relation to the 55 barrel.

A longitudinally perforated projectile is

employed, the same being adapted to slide freely upon the barrel 1. The rearward portion 13 of the projectile is of frusto-conical form, and to the base of said portion is 60 joined the smaller end of a similar portion 14 which merges into a cylindrical body 15, while the latter may have at its front end a rounded head 16.

In using the toy the projectile is placed 65 upon the barrel 1 and pushed rearwardly thereon so as to compress the spring 12, of which the normal length is preferably more than twice its length when compressed as shown in the drawings. As the projectile 70 approaches the position indicated, the conical portion 13 engages the upper side of the hook 10 and displaces it downwardly until the base of the conical portion passes the end of the hook. The hook then springs up 75 wardly and the end thereof engages the base of the portion 13 to retain the projectile upon the barrel, with the spring 12 under compression as shown. By pulling the trigger-portion 6 back toward the handle or 80 grip the hook is disengaged from the projectile so that the same may be forcibly propelled along the barrel by the spring 12.

The movement of the wire frame, in the 85 releasing of the projectile is somewhat peculiar. In Fig. 1 the dotted lines represent, with some exaggeration, the position of the parts when the projectile is released. It will be noted that there is little if any distortion of the front part of the trigger-loop, 90 the return-bend 7, arch-portion 8, stem 9 and hook 10, said parts forming in effect a bent lever, similar to a bell-crank, which is fulcrumed on the rounded front end of the breech-body 2. The rearward pull upon the 95 trigger serves to tilt upon its fulcrum the lever formed by the said parts, and thus force the hook 10 downward to release the projectile. The movement of the trigger causes the front part 5 of the grip to bow inwardly, 100 the lower arcuate portion of the trigger being also slightly distorted, and these portions of the frame act as springs or resilient parts to restore the members to normal position when the rearward pressure upon the 105 trigger is removed. On account of the described movement of the front part 5 of the grip or handle of the pistol, the trigger-pull necessary to discharge the same may be reduced by increasing the pressure of the 110 hand upon the grip, or the discharge may be effected solely by pressure upon the grip.

The trigger and grip or handle may thus be made large enough to be held conveniently by an adult or large child, and the pistol still be easily operated by a small child, whose hand would not be large enough to grasp the handle and pull the trigger in the usual way, but who could grasp the handle and effect the discharge of the projectile by increasing the pressure of the hand upon the grip. Furthermore, owing to the peculiar arrangement of the resilient frame-portions by which a comparatively great length of the wire is involved in the resilient action, the required distortion thereof in discharging the pistol is very slight, and is not liable to cause a permanent "set" of the parts in the distorted position. This enables the use of relatively soft or low-tempered wire in the frame, and facilitates the bending operations required in its manufacture.

The front end of the barrel 1 preferably has formed thereon a thread 17 similar to that of a wood-screw, and a stop-block 18 is provided which may be screwed onto the end of the barrel, when desired, to prevent the projectile being thrown off the barrel. This stop-block would be employed when the pistol was used indoors, or when given as a toy to small children. With the stop-block in position, the toy may be snapped without danger of injuring any person or object by the throwing of the projectile.

Now, having described my invention, what I claim and desire to secure by Letters Patent is:

1. In a toy pistol, an integral wire frame comprising a rectilinear barrel-portion, a looped breech-body adjoining the rear of the barrel, a grip-portion adjoining the breech-body, a trigger-loop adjacent to the grip, and a lever-portion fulcrumed on the breech-body, the end of the lever-portion

being engageable with a projectile on the barrel-portion, and the lever-portion being 45 tiltable on its fulcrum by distortion of the grip.

2. In a toy gun, an integral wire frame comprising a barrel-portion, a breech-body adjoining the rear end of the barrel, a grip-portion adjoining the breech-body, a trigger-loop adjacent to the grip, and a lever-portion having a hooked end adapted to engage and retain a projectile sliding on the barrel, the lever-portion connecting with the 50 trigger-loop and contacting slidably with the breech-body, and retaining means embracing the breech-body and the contacting portion of the lever, the lever being movable to release the projectile by distortion 55 of the trigger-loop and grip, whereby either of said parts may be employed to effect the release of the projectile.

3. In a toy gun, an integral wire barrel, breech-body, grip and trigger, a projectile-detent lever connected with the trigger, means for holding said lever in slidable contact with the breech-body, the said contacting parts having curved portions whereby their relative movement causes a tilting of 70 the lever, a perforate projectile slidably disposed on the barrel, and a spring disposed around the barrel and connected with the breech-body, the projectile having a conical portion with the base of which the end of 75 the detent-lever is engageable to retain the projectile in fixed position and with the spring under compression thereby.

In testimony whereof I have hereunto subscribed my name in the presence of two 80 witnesses.

O. C. MADISON.
